WASHING TANK FOR PHOTOGRAPHIC FILMS

Fred W. Deerfield, Baltimore, Md.

Application September 19, 1944, Serial No. 554,776

3 Claims. (Cl. 95—98)

1

This invention refers to photographing film treatment and more particularly to tanks for their development. It has among its objects to provide a washing tank for photographic film especially those of the X-ray type that will effectively clean off the substances and produce the effects for which washing thereof is intended. Another object is to have the structure made so that it will project cleaning water against the film completely over its front and rear area at an angle conducive to the best results. A further object is to support the films in a position that will enable them to drain off quickly and to vibrate them to shake off the matter to be removed.

A further object is to provide means for oscillating the film up and down and sidewise to prevent the stream of liquid from pitting or marking the film during the washing process.

A further object is to reduce the time required for washing the film.

Other objects will become apparent as the invention is more fully set forth.

In this invention the washing tank is made to support films in oscillating frames in a vertical position, and project water in streams in an angularly and downward direction, instead of with the films lying in running water of the tank in the conventional horizontal method.

In order to illustrate a form of this invention, reference is made to the attached specification and the appended drawings in which:

Figure 1 is a plan view, with cover removed, of a film washing tank embodying this invention;

Figure 2 is a side view of Figure 1 in section taken along the line 2—2;

Figure 3 is a sectional view taken along the line 3—3 of Figure 1, with cover in position, and

Figure 4 is a detail section of the tank and its mechanism for oscillating the film frames of the invention.

Similar reference characters refer to similar parts throughout the drawings.

In the construction indicated, 1 represents a watertight tank supported on legs 2, and having its bottom portion 3 angularly planed towards the middle, to provide drainage therefor. Water connections 4 are provided for supplying water under pressure to the helically formed auxiliary reservoirs 5 joined together by straps 27 and having legs 28 inside the tank. These reservoirs are arranged in a vertical position parallel to one another and perforated with orifices 6 adapted to squirt or spray the water from them in an angularly downward direction as indicated in Fig-

2

ure 2. An outlet connection 7 is used for emptying the tank from the bottom portion 3. A valve 8 and control mechanism 9 having a foot pedal 29 and catch 21 are used for controlling the water to the tank. The reservoirs 5 have a helical rectangular form which enables the water from the orifices to impinge water all over the films 10 and thereby positively detach and wash off the materials to be removed or diluted by the washing process. The films 10 are clipped in film holders 11 vertically and parallel to the reservoirs so as to be in the path of the water coming from the orifices. These film holders 11 are made with a truss 20 resting on cam members 12 rotated and supported on shafts 13. These shafts are rotated through the revolving of waterwheels 14 which are attached to them securely. The water wheels are in casings 15 mounted on the reservoirs 5 selected therefor and are operated by the water under pressure coming through the spouts 16. Outlets 17 allow the water used in the water wheels to escape to the tank and drain off with the other water used therein.

The operation of the device is relatively simple. The films are placed in the film holders 11 and clipped therein so they will be flat. The trusses of the film holders are then placed on the cam members and in position against them. The film holders are positioned in the tank 1 between the reservoirs 5 and with the films in line with the orifices 6. The water 18 under pressure is allowed to flow into the reservoirs. This starts the water wheels 14, turns the shafts 13, revolves the cams which in turn raises and lowers the film holders with the films in them. The raising and lowering of the film holders and films occurs in this instance during every revolution. The water from the orifices 6 squirting out at or spraying the films in a downward direction detaches the waste material and flows it downwardly. The movement, up and down and cross wise of the films shakes them and also brings different portions in front of the streams of water. This produces a very effective washing action without pitting or marking the films. The water reaches the bottom portion 3 of the tank 1 and passes out through the outlet 7. This process is continued until the films are properly washed off. When this is done, the films are removed from the device and are allowed to dry in a conventional manner.

While but one general form of the invention is shown in the drawings and described in the specifications, it is not desired to limit this application for a patent to this particular form or in any other

way otherwise than limited by the scope of the appended claims thereof, as it is appreciated that other forms of construction could be made that would use the same principles and come within the scope of the appended claims:

Having thus described the invention, what is claimed is:

1. An X-ray film washing comprising in combination, a tank, a film holder mounted in the tank, water feeding means having holes for directing streams of water in a downwardly and outwardly direction from the face of said water feeding means, cam means mounted in said tank, film holder supporting means positioned on said cams and rotated in an up and down and crosswise manner in the path of water from said water feeding means, and means for controlling the amount of water contacting the face of said X-ray film in a downwardly and outwardly manner.

2. A tank for washing X-ray films comprising in combination, a tank, removable film holders mounted in said tank, reservoir units supported in said tank, said reservoirs having holes positioned in helical form in the walls and directed downwardly and outwardly, a plurality of shafts positioned in said tank, means for rotating said shafts, cams mounted on and rotated by said shafts, trusses attached to said film holders and adapted to rest on said cams and be oscillated thereby, means for controlling the amount of a washing medium entering the reservoirs, and means for controlling the speed of said shafts and the movement of a film in an up and down and crosswise manner in relation to the holes in the walls of said reservoirs.

3. A tank for washing X-ray films comprising in combination, a tank, removable film holders

5 mounted in said tank, reservoir units supported in said tank, said reservoirs having holes positioned in helical form in the walls and directed downwardly and outwardly, a plurality of shafts having paddle wheels projecting within said reservoirs and rotated by the flow of washing medium through said reservoirs, cams mounted on and rotated by said shafts, trusses attached to said film holders and adapted to rest on said cams and be oscillated thereby, and means for controlling the amount of a washing medium entering the reservoirs and thereby controlling the speed with which a film is moved in an up, down and crosswise manner in relation to the holes in the walls 10 of said reservoirs.
